Primary Examiner—Ian Simmons*Assistant Examiner*—Charles Hanson(74) *Attorney, Agent, or Firm*—Malin, Haley & MiMaggio, P.A.(57) **CLAIM**

The ornamental design for a mixing bowl, as shown and described.

DESCRIPTION

FIG. 1 is a perspective view of the present invention, showing a mixing bowl of the new design;

FIG. 2 is a right side elevational view thereof; the left side is a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of FIG. 6 is included for the purpose of illustrating the complete article and forms no part of the claimed design.
